BERNARD C. DE LISLE AND GEORGE PEET MAIN, OF LOUGHBOROUGH,
ENGLAND.

CAR-COUPING.

SPECIFICATION forming part of Letters Patent No. 595,318, dated December 14, 1897.

Application filed February 24, 1897. Serial No. 624,860. (No model.) Patented in England August 10, 1894, No. 15,285.

To all whom it may concern:

Be it known that we, BERNARD C. DE LISLE and GEORGE PEET MAIN, subjects of the Queen of Great Britain, residing at Loughborough, 5 in the county of Leicester, England, have invented certain new and useful Improvements in Coupling Apparatus for Railway-Carriages and Wagons, of which the following is a full and complete specification, such as will enable 10 those skilled in the art to which it appertains to make and use the same.

This invention relates to car-couplers; and the object thereof is to provide an improved device of this class which is adapted for use 15 in connection with railway-cars and other vehicles.

The invention is the same for which Letters Patent were granted in Great Britain August 10, 1894, No. 15,285, and is fully disclosed in 20 the following specification, of which the accompanying drawings form a part, in which the separate parts of our improvement are designated by the same numerals of reference wherever found throughout the several views, 25 and in which—

Figure 1 is a plan view of a portion of the main frame at one end of a railway-car without the sides and flooring, the coupling apparatus being shown in position with the top of 30 a box which forms a part thereof; Fig. 2, a side view of one end of a railway-carriage with our improved coupling apparatus applied thereto; Fig. 3, an end view of the same; Fig. 4, a bottom plan view of a protecting- 35 plate which is secured to the under side of the box shown in Fig. 1; Fig. 5, an end view of a railway-carriage provided with our improved coupling apparatus; and Fig. 6, a view similar to Fig. 3, on an enlarged scale, showing 40 the locking-lever raised and the coupling-head and catch-hook shoved to one side in the position which it would occupy when the cars were being uncoupled or coupled.

The improved coupling apparatus consists 45 of the following parts: An oblong frame 1, having parallel sides, is secured to the main framing near the ends of each railway carriage or car. Within the frame a box 2 is free to slide to and fro. Beneath the top an 50 axle 3 projects, on which a clutch coupling-bar 4 rocks horizontally. Two springs 5 press

upon the sides of the bar, each spring being held by a stud 6, projecting from the top of the box. Other studs 7, projecting from the sides of the box, form stops for the springs. 55 The frame is provided with two rings at each end, on which coiled springs 8 are placed, against which the ends of the box rest. These springs hold the box and coupling-bar in a central position ready for coupling. 60

The outer end of each coupling-bar forms a horizontal catch-hook 9 and a projecting arm 10, between which the catch-hook of the coupling-bar of the next adjacent carriage or car engages when coupled. 65

The outer end of each bar is turned upward and slotted vertically at 9^a to receive the outer end of a locking-lever 11, rocking on an axle 11^b in a vertically-slotted bracket 12, secured to the front of the carriage or car framing. 70 The slot in the outer end of the bar is of sufficient width to allow the locking-lever to slide laterally in it when passing around a curve in the rails without straining the lever. The levers prevent the catch-hooks 9 from being 75 uncoupled when in use by any sudden jerk. The bracket 12 is also slotted vertically at the back parallel to the front of the framing. In this slot a notched lever 13 is free to rise and fall. The notched end engages with a vertical flange 14, projecting from the side of the coupling-bar, and holds the bar sidewise clear of the coupling-bar of the next carriage or car when uncoupled. At the same time an incline 13^a on the lower edge of the lever 13, 80 by engaging the end 11^a of the lever 11 back of the shaft 11^b, raises the outer end of locking-lever 11 above the vertical slot on the outer end of the coupling-bar. 85

The outer end of the lever 13 is hinged to 90 the lower end of a hand-lever 15, rocking on an axle projecting from the end of the carriage or car.

The upper end of the hand-lever slides in a guide 16, provided with a stud 16^a, on which 95 a lever 17 rocks, and the said lever 17 is provided with a shoulder 17^a, adapted to engage the said lever 15, and a spring 18, secured to the bracket, presses upon the lever 17 and holds the hand-lever locked when the coupling-bar has been moved sidewise. 100

When the coupling apparatus is applied to

the end of a car, the hand-lever 15 is held in the position shown at Fig. 5 by a spring 19. When the bar is coupled, the spring is hooked on a stud at the back of the hand-lever and 5 on a stud projecting from the lower end of the guide-bracket 16.

The back end of each coupling-bar 4 is provided with a pin 24, engaging in a slot 25 in the front end of a bar 20, sliding in slots in 10 the back of the frame 1 and box 2, and, passing through two portions of the main framing of the carriage or car, the back end of the bar is reduced and screw-threaded to receive a nut and lock-nut 21 and a coiled spring 22 15 between the framing and nuts.

The parts of the apparatus contained within the box 2 are protected by a plate 23, (shown at Fig. 4,) the plate being secured to the box by a screw at each corner. The center of the 20 plate, on the top side, is provided with a boss, forming a lower bearing for the axle 3, on which the bar 4 rocks. The plate 5 is also perforated to receive the lower ends of the two studs 6, holding the springs 5.

25 To uncouple the cars, one of the levers 15 shown at Fig. 3 being moved outward or one of the levers 15 shown at Fig. 5 being lowered by an attendant until the notch 17^a in the hand-lever 17, forced by the springs 18, 30 engages with the edge of the lever 15 the link 13 will raise the locking-lever 11 clear of the vertical slot on the outer end of the coupling-bar and will move the bar to the left and clear and release it from the bar of 35 the next adjacent carriage or car.

It will be understood that one of the coupling devices constructed as herein described is connected with each end of each of the cars or carriages to be coupled, and our improved coupler is simple in construction and 40 operation and well adapted to accomplish the result for which it is intended.

Having fully described our invention, we 45 claim as new and desire to secure by Letters Patent—

1. A coupling device for cars or carriages, consisting of an oblong frame mounted beneath the end of the car or carriage, a sliding box mounted therein, and held in position by 50 springs at each end thereof, a coupling-bar which passes through said box, and said frame, said coupling-bar being provided with a catch-hook at its outer end, and a projecting arm, and the outer end of said bar being 55 turned upwardly and slotted vertically, a vertically-slotted bracket secured to the end of the car or carriage, a locking-lever mounted therein, a notched lever operating in a slot 60

formed in said bracket and adapted to engage said locking-lever, and a hand-lever connected with said notched lever, said parts being constructed, combined and arranged, substantially as shown and described.

2. A coupling device for carriages or cars, consisting of an oblong frame mounted beneath the end of the car or carriage, a sliding box mounted therein, and held in position by springs at each end thereof, a coupling-bar which passes through said box, and said frame, said coupling-bar being provided with a catch-hook at its outer end, and a projecting arm, and the outer end of said bar being turned upwardly and slotted vertically, a vertically-slotted bracket secured to the end of the car or carriage, a locking-lever mounted 65 therein, a notched lever operating in a slot 70 formed in said bracket and adapted to engage said locking-lever, and a hand-lever connected with said notched lever, and a bracket through which said hand-lever passes, said bracket 75 being provided with a stud and a spring, substantially as shown and described.

3. A coupling device for carriages or cars, consisting of an oblong frame mounted beneath the end of the car or carriage, a sliding box mounted therein, and held in position by springs at each end thereof, a coupling-bar which passes through said box, and said frame, said coupling-bar being provided with a catch-hook at its outer end, and a projecting arm and the outer end of said bar being turned upwardly and slotted vertically, a vertically-slotted bracket secured to the end of the car or carriage, a locking-lever mounted 80 therein, a notched lever operating in a slot 85 formed in said bracket and adapted to engage the said locking-lever, and a hand-lever connected with said notched lever, and a bracket 90 through which said lever passes, said bracket being provided with a stud and a spring, and 95 said coupling-bar being pivotally connected with a sliding bar which is suitably supported, and provided with a spring at its rear end, and a set and a lock nut by which said spring 100 is held in position, substantially as shown 105 and described.

In testimony that we claim the foregoing as our invention we have signed our names, in presence of the subscribing witnesses, this 3d day of November, 1896.

BERNARD C. DE LISLE.
